United States Patent Office.

T. M. RICHARDSON, OF STOCKTON, MAINE.

Letters Patent No. 92,101, dated June 29, 1869.

TOBACCO-CUTTER.

The Schedule referred to in these Letters Patent and making part of the same.

To all whom it may concern:

Be it known that I, T. M. RICHARDSON, of Stockton, in the county of Waldo, and State of Maine, have invented a new and valuable Improvement in Tobacco-Cutters; and I do hereby declare that the following is a full, clear, and exact description of the construction and operation of the same, reference being had to the annexed drawings, making a part of this specification and to the letters and figures of reference marked thereon.

Figure 1, of the drawings, is a representation of a vertical section of my invention.

Figure 2 is a detail.

My invention relates to means for cutting tobacco, to prepare it for the pipe; and

It consists, mainly, in the construction and novel arrangement of devices by which a smoker may carry his tobacco in a box, and without removing therefrom cut the same sufficiently fine for the pipe.

The letter A of the drawings represents a cylinder, open at each end, and having its lower end corrugated, to form cutting-teeth, as shown on fig. 1.

Within this cylinder A, and near its bottom, I arrange cutters, marked c on the drawings, and which

somewhat represent the lips of an auger in form and mode of arrangement.

The letter B represents the box that holds the tobacco before it is cut, and the letter D the box that holds the tobacco after it is cut.

Each of these boxes is affixed upon the cylinder A, in such manner that they are removable at will; or they may be moved around said cylinder, as may be desirable.

To cut the tobacco, I turn the box B round and round upon the teeth and cutter of the cylinder.

The tobacco, when thus cut, passes to the box D, and is ready for use.

What I claim as my invention, and desire to secure by Letters Patent, is—

A tobacco cutting apparatus, having cylinder A, cutters c, and boxes B and D, constructed, combined, and arranged substantially as specified.

In testimony that I claim the above, I have hereunto subscribed my name in the presence of two witnesses.

Witnesses: T. M. RICHARDSON.
